UNITED STATES PATENT OFFICE.

GEORGE KELLY, OF MINERALPOINT, WISCONSIN.

LEG-REST.

SPECIFICATION forming part of Letters Patent No. 787,677, dated April 18, 1905.

Application filed July 21, 1903. Renewed March 6, 1905. Serial No. 248,659.

To all whom it may concern:

Be it known that I, GEORGE KELLY, a citizen of the United States, residing at Mineralpoint, in the county of Iowa and State of Wisconsin, have invented a new and useful Leg-Rest, of which the following is a specification.

This invention relates more particularly to that class of leg-rests employed in connection with rocking-chairs.

The object is to provide a combination structure that will constitute a comfortable rest and may be employed in connection with an ordinary rocking-chair, necessarily accommodating itself to the motion of the same and acting in unison therewith.

A still further object is to provide a rest the elements of which may be disassociated when not in use, so that one will constitute a receiver of general utility for papers and similar articles ordinarily employed by a person lounging in an easy-chair.

The construction which at present is considered preferable is illustrated in the accompanying drawings, wherein—

Figure 1 is a perspective view of the improved rest, showing the same applied to a chair. Fig. 2 is an end elevation of the same, the leg-supporting member being shown in section. Fig. 3 is a vertical longitudinal section, and Fig. 4 is a detail perspective view of the pivot-rod.

Similar reference-numerals indicate corresponding parts in all the figures of the drawings.

In the embodiment illustrated a rocker-frame is employed comprising spaced rockers 10, carrying upstanding spaced standards 11, said standards and rockers being connected by braces 12 and the standards being also connected at their lower ends by a cross-bar 13.

A leg-supporting member in the form of a platform 14 is pivoted between its ends to and between the standards. This pivotal connection is obtained by means of a rod 15, the ends of which engage in suitable seats 16, a vertical series of which are located in each standard, so that the height of the pivot-rod may be changed as desired. This rod is provided

with annular recesses 17, in which detachably engage suitable hinge-clips 18, carried by the under side of the leg-supporting member and embracing the rod. The supporting member is preferably upholstered at one end, as shown at 19, though the upholstering may extend the entire length or be dispensed with, as desired. Said upholstered end is contracted, as illustrated, and is connected by means of a hinge 20 with the projecting contracted neck 21 of a supplemental seat 22, constructed to be placed within any ordinary chair, upon the seat thereof.

The upper end of the frame is provided with a holder or receiver for papers and the like, said holder comprising a receptacle 23, the end walls of which are formed by the upper ends of the standards 11. This receptacle has an open side adapted to be closed by a cover 24, opening toward the supplemental seat and hinged to the lower portion of the receptacle. The outward movement of said cover is limited by suitable straps 25, and a latch 26 is adapted to hold it in closed relation.

The use of the structure as a rest will be clearly understood by reference to Fig. 1. The supplemental seat 22 is placed upon the ordinary seat of a rocking-chair and the occupant, sitting thereon, will hold said chair and rest in fixed relation, the legs being placed upon the supporting member. The chair can therefore be rocked and the support will move in unison, so as not to interfere with the motion, thereby constituting a comfortable rest. Papers or other articles can be placed in the holder in convenient reach of the occupant. When not in use, the supporting member and supplemental seat may be detached from the frame and the holder employed as a complete article of manufacture by itself.

From the foregoing it is thought that the construction, operation, and many advantages of the herein-described invention will be apparent to those skilled in the art without further description, and it will be understood that various changes in the size, shape, proportion, and minor details of construction

may be resorted to without departing from the spirit or sacrificing any of the advantages of the invention.

Having thus described my invention, what I claim as new, and desire to secure by Letters Patent, is—

1. In a leg-rest, the combination with a frame comprising rockers, standards mounted on the rockers, and connections between the standards, of a leg-supporting member pivotally connected with the standards, and means hingedly connected to the leg-supporting member and arranged to be frictionally supported on a chair for connecting such chair and leg-supporting member.
2. In a leg-rest, the combination with a leg-supporting member, of a movable support for the member, means for adjustably connecting the member and the support, and means hingedly connected to the leg-supporting member and arranged to be frictionally supported on a chair for connecting such chair and leg-supporting member.
3. In a leg-rest, the combination with a movable support, of a leg-supporting member having a vertical adjustment on the support, and a seat member hingedly connected to the leg-supporting member and arranged to be placed upon a chair-seat.
4. In a leg-rest, the combination with a frame comprising rockers carrying spaced upright standards, of a cross-bar extending completely across the space between and having its opposite ends adjustably mounted on the standards, a leg-supporting platform piv-

totally attached to and supported by the cross-bar, and means for hingedly connecting the leg-supporting platform to a chair.

5. In a leg-rest, the combination with a frame comprising rockers carrying spaced standards, of a cross-bar detachably mounted on the standards and vertically adjustable thereon, said cross-bar having annular grooves, and a leg-supporting platform having depending clips that detachably engage in the grooves of the cross-bar.

6. In a leg-rest, the combination with a leg-supporting member, of a rocker-frame for movably supporting the member, and means for detachably connecting the leg-supporting member to an ordinary chair, said means comprising a seat member that detachably rests upon the usual chair-seat.

7. In a leg-rest, the combination with a leg-supporting platform, of a rocker-frame having a pivotal connection with the platform, and means for detachably connecting the leg-supporting member to an ordinary rocking-chair, said means comprising a seat element that detachably rests upon the usual chair-seat and is hinged to one end of the supporting-platform.

In testimony that I claim the foregoing as my own I have hereto affixed my signature in the presence of two witnesses.

GEORGE KELLY.
